EXTENSION HANDLE FOR WRENCHES AND OTHER TOOLS

Original Filed Aug. 21, 1919

FIG. 1.

FIG. 2.

FIG. 3.

UNITED STATES PATENT OFFICE.

FRANK W. LOWNSBERY, OF SCRANTON, PENNSYLVANIA, ASSIGNOR OF ONE-THIRD TO STEPHEN S. SPRUKS AND ONE-THIRD TO WESLEY M. GARDNER, BOTH OF SCRANTON, PENNSYLVANIA.

EXTENSION HANDLE FOR WRENCHES AND OTHER TOOLS.

Application filed August 21, 1919, Serial No. 318,924. Renewed March 12, 1924.

To all whom it may concern:

Be it known that I, FRANK W. LOWNSBERY, a citizen of the United States, residing at Scranton, Lackawanna County, in the 5 State of Pennsylvania, have invented certain new and useful Improvements in Extension Handles for Wrenches and Other Tools, of which the following is a full, clear, and exact specification.

10 My invention relates to improvements in supplemental or extension handles for wrenches, spanners, and other tools whereby to increase the leverage or power with which the tool is operated; and the same has for 15 its object to provide a simple, efficient, and reliable handle which may be readily attached to and detached from a wrench or other tool.

Further, said invention has for its object 20 to provide a device of the character specified which is adapted for use in connection with tools having a flat or substantially flat handle or shank.

Further, said invention has for its object 25 to provide a device of the character specified which is adapted to receive the handle or shank of a tool, and to hold the same against accidental removal or detachment therefrom.

30 Further, said invention has for its object to provide a device of the character specified which may be made from an integral piece of metal.

Other objects will in part be obvious and 35 in part be pointed out hereinafter.

To the attainment of the aforesaid objects and ends my invention consists in the novel details of construction, and in the combination, connection, and arrangement 40 of parts hereinafter more fully described and then pointed out in the claims.

In the accompanying drawings showing an illustrative embodiment of my said invention,—

45 Figure 1 is a plan or top view showing an extension handle constructed according to and embodying my said invention, with a wrench in position thereon;

Fig. 2 is a side view thereof; and

50 Fig. 3 is an enlarged detail cross-section taken on the line 3—3 of Fig. 1.

In said drawings 10 designates the supplemental or extension handle, which is preferably formed of an integral piece of

metal, and comprises a flat elongated handle 55 or shank 11 provided at its outer or upper end with a flat transverse member 12 which extends inwardly from one of the longitudinal edges of the shank 11, across said shank, and has its free end terminating substantially in line with the opposite longitudinal edge of the shank. 13 denotes a similar member which is arranged a short distance in from the outer or upper end of the shank 11, and extends inwardly from the longitudinal edge of the shank opposite to that from which the member 12 extends. Both members 12, 13 are arranged parallel with each other and in the same horizontal plane, but above the plane of the surface of the shank 70 11, and have their free ends terminating substantially parallel and in line with their respective longitudinal edges of the shank 11.

At one side of the shank 11 is provided a locking device for retaining the wrench 75 or tool properly in position upon the extension handle 10. The said locking device comprises a small projection 14 which extends from the edge of the shank 11 having a circular socket 15 therein, and a reduced opening 16 in the base thereof. Within said socket 15 is disposed a stud 17 having a stem 18 extending therefrom and passing through the reduced opening 16 in the socket 15, and its outer end provided with 80 a head 19. 20 denotes a spring arranged about the stem 18, intermediate the stud 17 and the base of the socket 15, which serves to maintain said stud 17 normally projected.

90 21 denotes a wrench whose intermediate or handle portion is engaged below the inwardly-extending transverse members 12, 13, and locked in position upon the extension handle 10 by the spring-pressed stud 17. 95

To remove the wrench 21 from the extension handle 10 it merely becomes necessary to depress the spring-pressed locking stud 17, and move the inner end of the wrench outwardly, (in the direction of the 100 arrow, Fig. 1), whereupon the wrench may be removed from the extension handle 10.

It is to be noted that while I have shown and described my invention as embodied in an extension handle adapted to receive a 105 flat wrench or tool, that the same is not necessarily confined to such tools, as the same may be readily adapted to various

forms or tools having handles or shanks. Having thus described my said invention, what I claim and desire to secure by Letters Patent is:—

- 5 1. An extension handle for wrenches and analogous tools, comprising a shank and a plurality of members formed integrally therewith and arranged in spaced relation to each other and said shank; said members
10 extending from the opposite longitudinal edges of said shank transversely across the face of said shank and adapted to receive a wrench or other tool, substantially as specified.
- 15 2. An extension handle for wrenches and analogous tools comprising a flat shank, a pair of oppositely-extending transverse members arranged in spaced relation thereon adjacent to one end thereof and adapted
20 to receive a tool, a socket provided in said shank in proximity to one of said transverse members, a pin located in said socket and adapted to engage said tool, and spring means for maintaining said pin normally projected above the plane of said shank, substantially as specified.
- 25 3. An extension handle for wrenches and

analogous tools comprising a flat shank, and a pair of members formed integrally with said shank and arranged in spaced relation thereon adjacent to one end thereof; said members extending inwardly from the opposite longitudinal edges of said shank and adapted to receive a wrench or other tool, substantially as specified. 30

35 4. An extension handle for wrenches and analogous tools comprising a shank, a transverse member at one end thereof extending inwardly from one of the longitudinal edges of said shank, locking means provided along the same longitudinal edge of said shank, and a second member extending inwardly from the other longitudinal edge of said shank and arranged intermediate said first-named member and said locking means, substantially as specified. 40

45 Signed at the city of Scranton, Lackawanna County, in the State of Pennsylvania, this 21st day of July, one thousand nine hundred and nineteen.

FRANK W. LOWNSBERY.
